COMPOSITE PLANK

Anthony P. Miller, Pleasantville, N. J.

Application May 14, 1935, Serial No. 21,338

6 Claims. (Cl. 94—15)

This invention relates to composite planks which may have a wide and varied range of usefulness but which are particularly intended and peculiarly adapted for use in construction of 5 heavily travelled decking such for instance as the boardwalks commonly employed at seashore resorts.

These walks are usually elevated so that high tides may flow under them and while the use 10 of an all concrete walk is satisfactory from a standpoint of structural strength and durability, such walks are extremely hot and uncomfortable, lack resiliency, are tiring to walk upon and consequently discourage promenading and are 15 resultantly detrimental to the business of merchants and amusement concessions on the walk.

A wooden walk is quite comfortable to walk 20 upon. It is not nearly as hot as concrete but it does present a fire hazard and it is very expensive to keep in repair. Furthermore, in many 25 localities such for instance as Atlantic City, these boardwalks must be built to sustain very heavy loads such for instance as the travel of heavy fire engines over them in emergencies. With this 30 in mind the walks are built of extremely heavy, expensive wooden planking which must be replaced as soon as the surface thereof becomes splintered or split or worn down, or otherwise deteriorates to a condition where pedestrians might trip or injure themselves on the walk.

An object of the present invention is to provide a composite plank for use at such boardwalks which will be even stronger than the heavy wooden planks now employed; which will be substantially fire-proof; which will not become unduly hot in the sun and yet which will very materially reduce the cost of maintenance of the walk.

A feature of the invention is the use of a plank 40 having a base of concrete or similar material, the upper surface of this base being grooved for the reception of tread members or wear members of inexpensive construction which may be readily removed and replaced when they become 45 worn. The planks may be spaced apart in the fashion of the wood planking now used in order to provide ventilation, drainage and attraction. A walk constructed of these planks is comfortable to walk upon due to the resiliency of the 50 tread members and the only elements which are subject to wear under foot traffic or wheel traffic are the removable tread pieces which are in the first place inexpensive and which in the second place may be readily replaced when worn.

55 In accordance with one form of the invention

the longitudinally extending grooves in the tops of the planks are undercut and a series of wood or composite blocks disposed transversely of the grooves for tapered ends to key into the undercuts. With this type of construction although somewhat more expensive originally than fillers is even less expensive to maintain because a single worn block may be removed and replaced without disturbing its fellows. However it is within the scope of the invention to use elongated 10 wooden or rubber or composition fillers preformed to be slid endwise into the grooves or to use asbestos or similar material which may be preformed, molded or pressed into the grooves.

The invention may be more fully understood 15 from the following description in connection with the accompanying drawing wherein:—

Fig. 1 is plan view, partly broken away and in section illustrating one form of my invention,

Fig. 2 is an enlarged view in transverse section 20 on the line 2—2 of Fig. 1,

Fig. 3 is a view similar to Fig. 1 illustrating a modification, and

Fig. 4 is an enlarged transverse sectional view 25 on the line 4—4 of Fig. 3.

While as above suggested the grooves in the upper surface of the concrete bases of the planks may receive any suitable type of removable resilient tread member such as elongated wood or rubber members or may be filled with any suitable resilient wear resisting material which will afford the desired attraction, I have for illustrative purposes shown only the construction in which a multiplicity of transversely disposed, laterally abutting wooden blocks are employed 30 to afford the desired tread surface.

Referring more particularly to Figs. 1 and 2 of the drawing, 1 represents the flat elongated base of the plank and 2 the resilient filler or tread pieces. The base 1 is preferably of reinforced concrete, having a recess 3 in its upper face extending throughout its length preferably with undercut side walls to afford the general cross-sectional dove-tailed shape shown.

The filler pieces 2 may be of wood, rubber or any suitable composition. They correspond in longitudinal sectional shape to transverse sectional shape 3 of the grooves so that when located in this recess they will be keyed therein. 40 They are further preferably secured in the base by a thickness of waterproof cement or mastic cement 4 located under the filler pieces and around the ends thereof, thus keeping out moisture and effectively securing the filler pieces in 45 50 55

place. This mastic may likewise be employed between the filler blocks if desired.

To anchor the planks I preferably employ nails 5 driven into joists or other supports 6 and having heads 7 thereon which are forced into longitudinally extending grooves 8 in the sides of the plank. In driving the nails they are positioned close to the planks and when driven in sufficiently are bent laterally to project the heads of the 10 nails into the grooves. Adjacent planks are thus necessarily spaced a distance apart at least as great as the diameter of the shanks of the spikes or nails.

In the modification illustrated in Figs. 3 and 15 4 of the drawing the plank increased width provides room for three parallel grooves 14 corresponding to the groove 3. Grooves 9 are formed in the upper face of the base to give to the plank the appearance of a series of single planks, these 20 grooves being of a width corresponding to the spacing of the single planks shown in Fig. 1.

While three longitudinal tread receiving recesses 14 are shown, the plank may have two, 25 four or more if desired.

In the bottom of the grooves 9 drain openings 10 are provided and these drain openings are preferably given the downwardly flared or conical shape shown to prevent them from clogging.

The filler pieces 2 when of wood are preferably 30 formed with the grain running vertically and may be treated in any desired manner to lengthen their wearing qualities.

When a filler piece is worn or rotted, it can 35 be dug out of the recess and a three part filler piece inserted. This is illustrated in Fig. 1 of the drawing and the parts of the filler piece are given the reference characters 11, 12 and 13. The end sections 11 and 12 have tapered ends to key in the recess 3 and the center section 13 40 when forced or wedged into position between them insures their interlocking engagement with the base.

It will thus be seen that my improved plank 45 can be easily and cheaply kept in repair reducing the cost of maintenance to a minimum. These planks may be conveniently used for the replacement of one of the wooden planks now employed.

It will thus be seen that there is herein 50 described an article in which the several features of this invention are embodied, and which article in its action attains the various objects of the invention and is well suited to meet the requirements of practical use.

As many changes could be made in the above 55 construction, and many apparently widely different embodiments of this invention could be made without departing from the scope thereof, it is intended that all matter contained in the above

description or shown in the accompanying drawing shall be interpreted as illustrative and not in a limiting sense.

Having thus described my invention, what I claim as new and desire to secure by Letters 5 Patent is:—

1. A composite plank, including a preformed base having a recess in its upper face extending throughout its length and transversely positioned preformed filler pieces keyed in the recess, 10 said base having longitudinally extending grooves in its side edges adapted to receive the heads of securing devices driven into a support on which the plank is located.

2. A composite plank including a base having 15 a series of parallel recesses in its upper face, filler pieces keyed in the recesses, said base having longitudinal grooves in its upper face between the recesses to simulate separate planks and drain openings in the bottoms of the grooves. 20

3. A composite plank comprising a base having a dove-tailed recess in its upper face extending throughout its length and removable filler pieces in the recess at least one of said filler pieces consisting of end sections shaped to fit the side 25 walls of the recess and a center section between the end sections holding them in locked engagement with the base.

4. A multiple composite plank including a wide 30 flat preformed base having a plurality of longitudinally extending recesses in its upper face, tread members removably secured in said recesses, the spaces between said tread members being relatively narrow and said base having grooves in the spaces between the tread members 35 whereby to simulate separated composite planks.

5. A multiple composite plank including a wide flat preformed base having a plurality of longitudinally extending recesses in its upper face, 40 tread members removably secured in said recesses, the spaces between said tread members being relatively narrow and said base having grooves in the spaces between the tread members whereby to simulate separated composite planks, said last mentioned grooves having drain 45 holes therein.

6. A multiple composite plank including a wide flat preformed base having a plurality of longitudinally extending recesses in its upper face, tread members removably secured in said recesses, the spaces between said tread members being relatively narrow and said base having grooves in the spaces between the tread members whereby to simulate separated composite planks, the edges of said base having recesses 50 therein adapted to receive the heads of securing devices for retaining the composite plank in position.

ANTHONY P. MILLER.
